US00D784515S

(12) United States Design Patent (10) Patent No.: US D784,515 S
(45) Date of Patent: * Apr. 18, 2017

(54) HEADGEAR

(71) Applicant: Fisher & Paykel Healthcare Limited,
Auckland (NZ)

(72) Inventors: Craig Robert Prentice, Auckland (NZ);
Bernard Tsz Lun Ip, Auckland (NZ);
Mark Arvind McLaren, Auckland (NZ);
Kyle Gregory Brown, Auckland (NZ);
Chris Onin Limpin Hipolito,
Auckland (NZ); Mark Richard Tomlinson, Auckland (NZ); Melissa Catherine Bornholdt, Auckland (NZ)

(73) Assignee: FISHER & PAYKEL HEALTHCARE LIMITED, Auckland (NZ)

() Term: 15 Years

(21) Appl. No.: 29/540,683

(22) Filed: Sep. 25, 2015

(51) LOC (10) Cl. 29-02

(52) U.S. Cl.

USPC D24/110.1

(58) Field of Classification Search
